UNITED STATES PATENT OFFICE.

NICHOLAS A. KRETZER, OF LOUISVILLE, KENTUCKY.

LOCK-HANDLE MOUNTING.

Application filed March 18, 1921. Serial No. 453,415.

To all whom it may concern:

Be it known that I, NICHOLAS A. KRETZER, a citizen of the United States, residing at Louisville, in the county of Jefferson and State of Kentucky, have invented a new and useful Lock-Handle Mounting, of which the following is a specification.

In mounting locks on doors, the stem of the handle which projects through the face of the door is usually passed through a washer or disk fastened to the face of the door, and heretofore this washer or disk has usually been fastened in place by several ordinary wood screws, ordinarily from two to four in number. This has frequently served as an invitation to remove the screws and the washer, thus making an unsightly place on the door; this invitation has been especially strong in case of the inside knob of coin-controlled locks, because of the expected possibility of abstracting money from the lock through the hole thus opened.

It is the object of my invention to make it impossible to remove this disk or washer by fastening the washer in place by non-accessible means, and at the same time to improve the appearance by eliminating the exposed fastening screws so that the washer or disk will be entirely smooth on its exposed surface. At the same time, it is my object by this same fastening means to locate the washer in a special position with respect to the lock proper so that the stem for the knob will necessarily be in proper alignment with the part which receives it and binding of the lock by having these parts out of alignment will be avoided.

The accompanying drawing illustrates my invention: Fig. 1 is an edge elevation of a part of a door provided with a coin-controlled lock in which the washer through which the stem of the inside knob projects is mounted in accordance with my invention, part of the door being in section and part of the lock casing being broken away; and Fig. 2 is a section on a smaller scale on the line 2—2 of Fig. 1.

The door 10 has a lock plate 11 fastened to its outer face by screws 12, and on this lock plate is suitably mounted a lock casing 13, as shown by an interlocking tongue and groove 14 at the top and a screw 15 at the bottom passing through a lug 16 projecting inward from the bottom of the casing and overlapping the lock plate 11. The casing 13 fits over and entirely conceals

the locking plate 11. Within the casing 13 is a suitable locking mechanism, not shown, which locking mechanism may be operated either by an outside knob 17 or an inside knob or handle 18, the operation of the lock by the knob 17 depending on some coin-control in the case of many coil-operated locks. The casing 13 is provided at the bottom with a removable locked door 19, which is open to remove the accumulated coins, and through the opening of which access to the screw 15 is obtained.

The stem 20 for the inside knob 18 projects through the door into cooperation with a stem-receiving part 21 of the locking mechanism. This stem passes through a disk or washer 22 which lies against the inner face of the door 10. This is the washer which has ordinarily heretofore been held in place by a plurality of wood screws. I provide no wood screws for holding this washer in place, but make its outer surface entirely smooth. This washer has a central threaded hole 23, with the threads of which an externally threaded sleeve 24 passing through the door cooperates. The sleeve 24 loosely surrounds the stem 20, and is provided at its inner end with a polygonal head 25 which bears against the exposed face of the locking plate 12. By turning the sleeve 24 by its head 25, the washer 22 is drawn tightly against the inner face of the door 10, and the head 25 thus draws tightly against the locking plate 11. This is done from the outside, and can only be done when the lock casing 13 is removed. To prevent possibility of turning the washer 24 while it is against the door 10, it is provided with an eccentrically located pin 26 which extends into a correspondingly located hole 27 in the inner face of the door 10, as is clear from Fig. 1. The sleeve 24 is definitely located with respect to the lock plate 11, and so definitely locates the disk or washer 22 with respect to such lock plate, to hold the stem 20 in proper alignment with the stem-receiving part 21 of the lock, without possibility of these parts getting out of alignment and producing binding of the lock because of any inaccuracy in putting in the wood screws which are ordinarily used for fastening the disk or washer in place.

The outer end of the stem 20 is carried in a sleeve 28 which is screw-mounted in the outer end of the threaded hole 23, the sleeve

24 projecting but part way through such hole to leave room for such other sleeve 28. The stem 20 is freely turnable within the sleeve 28, but is held against axial movement relative thereto by abutting shoulders 29 and by a cross pin 30. After the washer 22 has been put in place, and the casing 13 with its locking parts have been mounted in place on the lock plate 11, the stem 20 is 10 inserted through the washer 22 and sleeve 24 into the stem-receiving part 21, and the sleeve 28 is screwed into the outer end of the hole 23, and preferably tightened by a suitable spanner wrench for which a hole 15 31 is provided. This makes a slightly construction, because of the smoothness of the exposed face of the disk or washer 22, and makes it impossible to remove such disk or washer from the inside of the door.

20 I claim:

1. In a mounting for a lock-handle stem, the combination of a non-rotatable washer or disk for engaging the face of the door, said washer or disk being provided with an 25 internally threaded opening through which the stem of the handle may project, and a sleeve surrounding said stem projecting through the door and beyond the face thereof and having threaded engagement with the hole in said washer, said sleeve at its 30 other end being provided with a head for cooperating with a suitable abutment to clamp said washer or disk against the face of the door.

35 2. In a mounting for a lock-handle stem, the combination of a washer or disk for engaging the face of the door, said washer or disk being provided with an internally threaded hole through which the stem of 40 the handle may project, and a sleeve surrounding said stem projecting through the door and beyond the face thereof and having threaded engagement with the hole in said washer, said sleeve at its other end 45 being provided with a head for cooperating with a suitable abutment to clamp said washer or disk against the face of the door, said washer or disk having an eccentrically located pin for projecting into a correspondingly located hole in the door to prevent the washer or disk from turning.

50 3. In a mounting for a lock handle stem, the combination of a washer or disk for engaging the face of the door, said washer or disk being provided with a hole through 55 which the stem or handle may project, a sleeve surrounding said stem and having threaded engagement with the inner end of the hole in said washer, said sleeve at its 60 other end being provided with a head for cooperating with a suitable abutment to clamp the washer or disk against the face of the door, a second sleeve in which the lock handle stem is rotatably mounted, said sec-

ond sleeve having a screw threaded mounting on the outer end of said hole, and abutment members on the handle stem arranged on opposite sides of said second sleeve. 65

4. In a mounting for a lock-handle stem, the combination of a washer or disk for engaging the face of the door, said washer or disk being provided with a hole through which the stem of the handle may project, a sleeve surrounding said stem and having threaded engagement with the inner end of 70 the hole in said washer, said sleeve at its other end being provided with a head for cooperating with a suitable abutment to clamp said washer or disk against the face of the door, and a second sleeve in which the 75 lock-handle stem is rotatably mounted, said second sleeve having a screw mounting in the outer end of said hole.

5. In a lock, a locking plate arranged to be fastened to a door on one face, a lock 85 casing removably mounted on said locking plate and provided with locking parts including a stem-receiving part, a washer or disk arranged to bear against the other face of the door and provided with a central internally threaded hole for the reception of 90 a lock-handle stem which cooperates with said stem-receiving part and projects through said hole and through a hole in the door, and a sleeve arranged to pass through 95 the lock plate and the hole in the door and to project beyond the face thereof to have a threaded engagement with the hole in said disk or washer, said sleeve being provided with a head for bearing against said lock- 100 ing plate.

6. In a lock, a locking plate arranged to be fastened to a door on one face, a lock casing removably mounted on said locking plate and provided with locking parts including a stem-receiving part, a washer or disk arranged to bear against the other face of the door and provided with a central internally threaded hole for the reception of 105 a lock-handle stem which cooperates with 110 said stem-receiving part and projects through said hole and through a hole in the door, and a sleeve arranged to pass through the lock plate and the hole in the door and to project beyond the face thereof to have 115 a threaded engagement with the hole in said disk or washer, said sleeve being provided with a head for bearing against said locking plate, and said washer or disk having an eccentrically located pin for projecting into 120 a correspondingly located hole in the door to prevent the washer or disk from turning.

In witness whereof, I have hereunto set my hand at Louisville, Kentucky.

NICHOLAS A. KRETZER.
